UNITED STATES PATENT OFFICE.

CHARLES O. KNUDSEN, OF BROOKLYN, NEW YORK.

SHIP-REPAIRING MEANS.

1,263,566.

Specification of Letters Patent. Patented Apr. 23, 1918.

Application filed October 31, 1917. Serial No. 199,398.

To all whom it may concern:

Be it known that I, CHARLES O. KNUDSEN, a citizen of the United States of America, residing at Brooklyn, New York, have invented a new and useful Ship-Repairing Means, of which the following is a specification.

This invention relates to the repairing of injuries to ships' hulls, occasioned, for instance, by explosions, collisions, etc.

One of the objects of the invention is to provide repair means of this character which may be readily stored in compact form on board ship, and which when needed, may be quickly applied to the injured portion of the ship.

Other objects are to provide a repair which can be made substantially watertight, which will resist the pressure and strains, which may be conformed to the portions of the hull to which it is applied, and which can be readily and firmly secured in place.

Briefly stated, the invention comprises what I have termed a "patch" of flexible material which is suitably reinforced and which is provided with means by which the same may be positioned and supported to cover an injury in a ship's hull. This patch is normally rolled in compact form and in case of injury is unrolled at the side of the ship so as to cover the damaged area. The reinforcements are preferably transversely disposed so as not to interfere with this rolling and unrolling of the patch and the supporting means are so disposed that they will remain on the outside of the roll when the patch is rolled up in compact form.

Another feature of the invention is the provision of means for engagement with the reinforcements at the inside of the ship's hull to secure the patch more firmly in place.

Other features of the invention are special reinforcements for application over the patch to strengthen the same, to prevent leakage around the edges of the same and to shape the patch to different curvatures of the ship's hull.

The foregoing features and additional features will be made clear in the following specification and accompanying drawings which illustrate the invention embodied in a practical form.

In these drawings:

Figures 1 and 1^a are fragmentary views of

a ship's hull having the repair means of my invention applied thereto.

Figs. 2, 3 and 4 are outside, edge and side views of the patch as unrolled to cover a damaged section of hull.

Fig. 5, is a face view of a reinforcing plate for application over the outside of the patch.

Figs. 6 and 7 are plan and edge views respectively of a spring shaping member for conforming the patch to a bulging or convex portion of the hull.

Figs. 8 and 9 are similar views of a spring reinforcement for conforming the patch to a concave section of the hull.

Figs. 10 and 10^a are fragmentary sectional views of a ship's hull taken on different planes and showing these spring shaping devices applied to reversely curved portions of the hull.

Figs. 11 and 12 are edge and face views of an auxiliary patch strip.

Figs. 13 and 14 are similar views of a sectional reinforcing plate.

Fig. 15 is a view of the patch rolled up for storing.

The body of the patch or covering element 15 is made up of canvas or other suitable flexible material, a sufficient number of plies or layers being employed to insure the necessary strength and water-resistive ability and the fabric being waterproofed or otherwise treated to render it suitable for this purpose. This sheet of material is reinforced, preferably at the top and the bottom thereof by bars 16, 17 incorporated in or attached to the edge portions of the material and also by transverse struts or bars 18 attached to the patch by riveting or otherwise as indicated at 19 and disposed within the borders of the patch. This transverse arrangement of the reinforcing bars enables the patch being rolled up when not in use and gives a certain longitudinal stiffness to the roll which facilitates handling of the same and the quick shifting of the rolled patch to any point where it is needed.

The patch is supported over the side of the ship in the case illustrated by cables 20 and 21 attached respectively to the upper corner and intermediate portions of the patch. These cables being preferably provided with hooks or the like supporting elements which may be quickly engaged over

the rail of the ship or any other convenient point of attachment. Cables 23 and 24 attached respectively to the upper corner portions and lower side portions of the patch 5 provide means for holding the sides of the patch in place against the ship's hull and also provide means by which the patch may be shifted longitudinally "fore" or "aft". To facilitate handling these "fore" and "aft" 10 cables may be joined in a common cable as illustrated at 25 in Fig. 1.

The patch is held down at the bottom by cables 26-27 attached respectively to the corner and intermediate portions at the 15 lower edge of the patch and which cables may be united to a common shackle 28 from which a cable 29 extends under the hull of the ship to the opposite side thereof. The patch may also be steadied at the bottom by cables 30 connected to the lower corner 20 portions of the patch and designed to be carried on divergent angles beneath the keel to the opposite side of the ship. Said cables 30 may be formed as continuations of the 25 upper cables 20.

In practice the patch is rolled into compact form and stored in a conveniently accessible place, such as on the hatch covers, from which point it may be readily carried 30 "fore" and "aft" or to either side as the case may require. The patches are rolled from the bottom upward and usually with the inside of the patch toward the inside of the roll and the ends of the supporting and 35 steadyng cables are preferably left exposed as indicated in Fig. 15. In case of an injury to the ship's hull, as by torpedoing or the like, the rolled patch is carried to the point of injury and then after hooking the 40 supporting cables over the rail or other convenient support, the roll is carried outward by suitable tackle and allowed to unroll in such a position as to cover the damaged area. The patch is lowered far enough out from 45 the side of the ship to enable the same to pass clear down below the injury, the inward rush of water into the injured portion of the hull being ordinarily sufficient to carry the patch inward into position over 50 the aperture. Before the roll is dropped overboard the "fore" and "aft" stays and the connections for pulling the patch downward are usually carried to convenient points on the ship from where they can be 55 drawn taut as soon as the patch unrolls and covers the hole in the ship's side. The bottom cable or cables may be placed by retaining the ends of said cables when the roll is cast over and carrying such ends around the 60 bow or stern, whichever is nearest, as the case may be, and then drawing said cable taut from the opposite side of the ship.

The reinforcement prevents the patch from giving way under the pressure of the water 65 and these reinforcements may be used also

as a means for anchoring the patch from the inside of the ship. Thus in Figs. 3, 4 and 10 I have shown these reinforcements provided with bolts 31 which may be engaged with beams or spars 32 placed so as 70 to span or bridge the openings at the inside of the hole.

To prevent leakage at the edges of the patches or wherever necessary, I may make use of smaller auxiliary patches in the shape 75 of relatively narrow strips of flexible material 33 which may be lowered so as to cover the edge portions of the main patch as indicated in Figs. 1 and 1^a and be steadied at the top and bottom as by means of suitable 80 cables or connections 34.

Other external reinforcements may be provided as the reinforcing plates illustrated at 35 in Figs. 1 and 5, said plates being applied over the patch and being of sufficient size to lend the necessary strength and reinforcement to the patch. For convenience in handling and storing, these reinforcement plates may be made in sections 85 as indicated in Figs. 1^a, 13 and 14, said sections 35^a, 35^b being joined when needed, for instance, by means of lugs 36 on one section engaging in properly disposed openings 37 in the other section. These reinforcements may also be steadied at the top and the bottom as indicated at 38 in Figs. 1 and 1^a.

At certain points in the ship's hull, for instance, at the bow and stern, special reinforcing means may be necessary to hold the patch properly fitted to the ship's hull. For 100 this purpose I may employ the shaping devices illustrated more particularly in Fig. 10 and comprising in the first instance concavely curved shaping elements 39 for holding the patch against bulging on convexed 105 portions of the hull and the convex shaping devices 40 acting in a similar fashion to press the patch against concaved portions of the ship's hull. These patches may also be of spring metal and bowed as indicated in 110 Figs. 6-7 and 8-9 so as to act in the capacity of springs to yieldingly press the patches against the hull and the supports 41 which carry these spring shaping elements may be off-set from the contact surfaces of the elements so as to exert sufficient pressure when 115 tension is applied to the supporting cables 42 connected to opposite ends of the supporting bars 41.

What I claim is:

1. Ship repairing means comprising a patch for covering the damaged portion of a vessel, means for supporting and positioning said patch over the damaged portion, and a separate auxiliary patch of flexible material engageable over the edge portions of the main patch and provided with means for positioning and supporting the same in reference to the main patch. 125

2. Ship repairing means comprising a 130

- patch of flexible water-tight material provided with means for supporting the same over the damaged portion of a vessel to stop the inflow of water, and an imperforate reinforcing plate applied over the outside of said patch for taking the strain of pressure off the leak stopping patch.
3. Ship repairing means comprising a patch of flexible material provided with means for supporting the same over the damaged portion of a vessel, and a curved shaping member applied over the outside of said patch for conforming said patch to the curvature of the hull of the vessel.
- 10 4. Ship repairing means comprising a patch of flexible material provided with means for supporting the same over the

damaged portion of a vessel, and a curved spring shaping member applied over the patch and yieldingly conforming the patch 20 to the curvature of the hull.

5. Ship repairing means comprising a patch of flexible material provided with means for supporting the same over the damaged portion of a vessel, a curved spring 25 shaping member for yieldingly holding the patch over curved portions of the ship's hull, supporting means for said spring shaping device offset from the contacting plane of such device whereby to force said 30 shaping device into engagement with the patch.

CHARLES O. KNUDSEN.
